UNITED STATES PATENT OFFICE.

SAMUEL N. LEOPOLD, OF CHICAGO, ILLINOIS, ASSIGNOR TO ROSE DISPLAY BOX COMPANY, OF CHICAGO, ILLINOIS, A CORPORATION OF ILLINOIS.

DISPLAY BOX.

Application filed April 1, 1926. Serial No. 98,967.

This invention relates to a new and improved display box, and more particularly to the type of box in which the box portion, serving as a cover when the box is closed, 5 serves as a support when the box is open.

Boxes of this type have heretofore been made in which the portion serving as both cover and support is provided with downwardly extending flanges on the end and a portion only of the side. It is impossible to extend these flanges along the full length of the side since this would prevent the member from being folded under to serve as a display support. When the member is 10 used as a cover therefor it only encloses a portion of the side edges and the unenclosed portions tend to spring outwardly and provide openings between the side and cover. Also the box has little rigidity and does not 15 properly protect its contents. With some types of box of this character the combination cover and support member is integrally connected to the box bottom and extends upwardly inside the box end. With 20 this type of box, as usually constructed, there is no box element which serves to maintain the over-hanging cover end flange in contact with the adjacent box end. This feature also renders the box somewhat unstable. 25

It is an object of the present invention to provide a new and improved display box or carton, having a cover member adapted to serve as a support when the box is in the 30 display position.

It is an additional object to provide a box of this character in which members are provided fully closing the corner between the box sides and box top throughout the length 35 of this corner.

It is a further object to provide a box of this type in which means are provided for maintaining the cover portion against the adjacent end portion of the box.

It is a still further object to provide a box of this type having a display portion integrally connected to the box, the box having means to maintain this portion against an adjacent box end.

Other and further objects will appear as the description proceeds.

I have illustrated a preferred embodiment

of my invention in the accompanying drawings, in which

Figure 1 is a perspective view of the box 55 in the display position;

Figure 2 is a perspective view of the box in closed position; and

Figure 3 is a view of the flat box blank.

The box comprises the bottom 11 and the 60 sides 12 and 13, which are integrally connected to the box on the lines 14 and 15. The tabs 16 and 17 are integrally connected to the ends of the side member 13, and the similar tabs 18 and 19 are connected to the 65 side member 12. The display flap 20 is connected to the bottom along the line 21, and is provided with scored line 22. The top member 23 is connected to the bottom along line 24 and is provided with the scored lines 70 25 and 26. An intermediate portion is formed between the scored lines 24 and 25, which portion integrally connects the top and bottom. The top member is provided with the end portion 27, which latter is connected to the top along line 28 and is scored at 29 and 30. The tabs 31 and 32 are connected to the opposite sides of the top portion along lines 33 and 34, and are provided with angular edges 35 and 36. The tabs 31 and 32 are provided with the extension 80 flaps 37 and 38 respectively. The tabs 18 and 19 are provided with cuts 39 and 40 respectively, and the tabs 16 and 17 are provided with the locking portions 41 and 42 85 respectively.

In folding the box for use the side members 12 and 13 are folded upwardly along lines 14 and 15. The display portion 20 is bent upwardly along line 21 and the tabs 90 16 and 18 are swung inwardly to form the end of the box, the member 41 being inserted in the cut 39. The cover member 23 is swung upwardly about line 24 and the tabs 17 and 19 are swung inwardly and the 95 notch 42 inserted in cut 40 to form the other end of the box. The flanges 43 and 44 are folded down so as to extend horizontally inward. The extension 27 is folded inwardly on line 28 and the tabs 31 and 32 100 are folded on lines 33 and 34, the extensions 37 and 38 being placed inside of the folded portion 27. The portion 27 is then folded upon itself upon line 29, thus enclosing the

extensions 37 and 38, and the end edge of the portion 27 is folded on line 30 sufficiently to slip under the struck-up tabs 45 and 46.

After the box is filled with the desired commodity, the display portion 20 is folded down on line 22, resting on the material in the box and on the flanges 43 and 44. The top is then folded down on line 25 and serves to close the box. The portion 27 extends beyond the opposite end of the box and the portions 31 and 32 extend beside the sides of the box, as shown in Figure 2.

The corners between the sides and top of the box are fully closed by the flanges 43 and 44 which have been indicated in broken lines in Figure 2. The ends of these flanges also fit against the cover member at line 25 where it is bent down over the box. They thus serve to maintain the lower or connecting portion of the top against the end of the box formed by the tabs 17 and 19. Similarly, the other ends of the flanges 43 and 44 engage against the display member 20 on the line 21, and when the box is in the display position, as in Figure 1, they maintain the member 20 against the end of the box formed by the tabs 16 and 18.

To open the box for display the cover is lifted and swung about line 25 until the portion between the line 25 and the line 26 is in engagement with the front of the box. The cover is then swung further about the line 26 to bring it to the position shown in Figure 1, in which the angular edge 35 of the member 31, and the similar edge 36 of the member 32, rest on the box support. Similarly, the edge 29 of the top end portion 27 serves as a support. This supporting portion is quite rigid, due to the double portion extending across the end which is also stiffened by the inturned tabs 37 and 38.

The flanges 43 and 44 are highly important in rendering the box satisfactory, both for display and for packing purposes. These flanges fully close the box when the top is down and also stiffen the box longitudinally and maintain the overhanging portion of the top in engagement with the adjacent end of the box. When the box is open they also have the important function of maintaining the display portion in the proper position, even after a large portion of the contents of the box are removed.

I claim:

1. A display box or the like, comprising a body portion having a bottom, sides and ends, an intermediate portion integrally connected to one end of the bottom and extending loosely up inside the adjacent end of the box, a cover connected to said intermediate portion, and inturned portions upon the upper edges of the sides engaging the intermediate portion to hold it in contact with the adjacent end of the box. 55

60 2. A display box or the like, comprising a body portion having a bottom, sides and ends, an intermediate portion integrally connected to one end of the bottom and extending loosely up inside the adjacent end of the box, a cover connected to said intermediate portion, and inturned portions upon the upper edges of the sides engaging the line of junction between the intermediate portion and the cover to hold the intermediate portion and connected end of the cover 70 against the adjacent end of the box. 75

80 3. A display box or the like, comprising a body portion having a bottom, sides and ends, an intermediate portion integrally connected to one end of the bottom and extending loosely up inside the adjacent end of the box, a cover connected to said intermediate portion, a second intermediate portion similarly located at the other end of the box, a display flap secured to said second intermediate portion, and inturned portions upon the upper edges of the sides engaging the intermediate portions to hold them in contact with the adjacent ends of the box. 85

90 4. A display box or the like, comprising a body portion having a bottom, sides and ends, an intermediate portion integrally connected to one end of the bottom and extending loosely up inside the adjacent end of the box, a cover connected to said intermediate portion, downturned flanges under the ends and a portion only of the sides of the cover, and inturned flanges extending the length of said sides, said flanges engaging the intermediate portion to hold it against 95 the adjacent end of the box and also serving to close the corners between the sides and the cover. 100

Signed at Chicago, Illinois, this 29th day of March, 1926.

SAMUEL N. LEOPOLD.
